(57) **CLAIM**

The ornamental design for a tabletop mount for display panel, as shown and described.

DESCRIPTION

FIG. 1 is a top perspective view of a tabletop mount for display panel;

FIG. 2 is another top perspective view thereof shown with the environment of a display panel mounted thereon;

FIG. 3 is a front elevation view of the tabletop mount for display panel of FIG. 1;

FIG. 4 is a rear elevation view thereof;

FIG. 5 is a right elevation view thereof;

FIG. 6 is a left elevation view thereof;

FIG. 7 is a top plan view thereof; and

FIG. 8 is a bottom plan view thereof;

FIG. 9 is a front elevation view thereof shown mounted to the environment of a surface with the environment of a display panel mounted thereon;

FIG. 10 is a rear elevation view thereof shown mounted to the environment of a surface with the environment of a display panel mounted thereon; and,

FIG. 11 is a left elevation view thereof shown mounted to the environment of a surface with the environment of a display panel mounted thereon.

The broken lines showing a display panel, fastener and mounting surface in FIGS. 2 and 9–11 represent unclaimed environment that form no part of the claimed design. All remaining broken lines illustrate portions of the tabletop mount for display panel that form no part of the claimed design.
